UNITED STATES PATENT OFFICE.

THOMAS BEASLEY, OF MERTON, ENGLAND.

SURGICAL TRUSS AND THE LIKE.

Application filed March 5, 1923. Serial No. 622,995.

To all whom it may concern:

Be it known that I, THOMAS BEASLEY, a subject of the King of Great Britain, residing at 36 Meadow Road, Merton, in the 5 county of Surrey, in the Kingdom of England, have invented certain new and useful Improvements in or Relating to Surgical Trusses and the like, of which the following is a specification.

10 This invention relates to improvements in surgical trusses and the like of the type in which detachable and adjustably inflatable pads are adapted to be adjustably secured on a belt or the like.

15 The object of this invention is to provide an improved surgical truss of the above type which can be worn with the greatest comfort by the weakest and most sensitive persons to obviate the objections of rupture 20 or act as a preventative of such complaints.

A further object is to provide a device of the above character in which the means for regulating the pressure in the inflatable pads is such that the parts may be adjusted 25 and the pressure may be regulated to suit the wearer, for instance, whilst the device is being worn.

30 A further object is to provide inflatable pads with a backing of substantially non-resilient material so shaped that it can be readily placed on any desired body belt, such as belts of webbing, leather or rubber, thus providing a truss which can be adapted to be worn at any time for instance by day, 35 night or during bathing.

According to this invention a screw adjustable valve is connected by a flexible connection to a pad which is fitted or formed on a plate or backing so shaped, such as by 40 having substantially vertically arranged slots, that the said pad may be slidably arranged on and be automatically secured to a body belt or the like so that the pads can be readily fitted and adjusted on the said 45 belt and the pressure of the pads can be regulated whilst in use.

The invention will now be described with reference to the accompanying drawings, in which:—

50 Figure 1 is a perspective view of one form of double truss constructed according to this invention;

55 Figure 2 is a front elevation of one of the pads and part of the securing belt drawn to a larger scale;

Figure 3 is an elevation of the inner side of the pad shown in Figure 2;

Figure 4 is a cross section taken substantially on the line *a—a* of Figure 3;

Figure 5 is a sectional elevation of one of 60 the interior bladders showing my preferred form of valve and pump attached thereto;

Figure 6 is an elevation of a modified form of pad;

Figure 7 is an elevation of the pad shown 65 in Figure 6 looking in the reverse direction;

Figure 8 is a vertical section thereof;

Figure 9 is a view similar to Figure 2 of a further modified construction;

Figure 10 is a vertical section thereof; 70

Figure 11 is a sectional detail of a modified form of valve;

Fig. 12 is a sectional view illustrating a slightly modified form of pad.

As shown, more particularly in Figures 1 75

to 4, each pad member comprises a casing member 1 for a bladder or the like 2 which casing member is adapted to be secured around its edges between a flat back or base plate 3 and a clamping ring 4. The base 80

plate 3 is of any suitable material preferably metal such as aluminum, but it will be understood that it may be formed with any non-resilient or partly resilient material, 85

such as leather, wood or any suitable composition. The edges of the casing member 1 are firmly clamped between the plates 3 and 4, by means of screws 5 adapted to screw into the said ring 4. The back plate 90

3 is preferably of substantially circular shape and is provided at opposite sides with slots 6 preferably of arcuate shape for the reception of the body belt 7 which is threaded therethrough. This body belt 7 which 95

may be of the usual construction and of webbing or elastic material is fitted with a buckle 8 whereby it can be adjusted in the usual manner. Each back plate 3 is also formed with an intermediately arranged slot 9 for the reception of one end of the belt 10 which is adapted to pass around the hips 100

10 which is adapted to pass around the hips in the usual manner. One end of this hip belt 10 is secured to the plate 3 preferably by hemming over the end of the belt and the other end is secured by means of a buckle 11 105

to a loop-strap 12 preferably slidably arranged on the body belt 7. The bladder or 110

the like 2, which is adapted to fit within the hemispherically or otherwise shaped casing 1 of each pad member is preferably con-

110

structed of rubber and formed or provided with a resilient tube 13. This resilient tube 13 which is arranged at any convenient part of the bladder 2 is adapted to project 5 through a hole 14 in the casing 1 which latter is preferably constructed of washleather or the like. If desired, the casing 1 may be provided with a washleather or like flap 15 to prevent the rubbing of the lower end of 10 the plate 5 against the wearer. The outer end of each resilient tube 13 is fitted with a valve of any convenient form. In this instance the valve comprises a pair of threadedly connecting members 16 and 17 constructed 15 of vulcanite or other suitable material. The member 16 is adapted to be secured in any convenient manner to the resilient tube 13 and the member 17 is provided with a threaded nipple 18 on which is 20 adapted to be screwed any convenient form of pump indicated at 19, in Figure 5. Between the members 16 and 17 is arranged a ball valve 20 which is adapted to operate in the manner to be hereinafter described. The 25 pump 19 is constructed of resilient material and is formed with a bulb portion in one end on which is fitted a suitable non-return valve 21, the other end being fitted with a vulcanite threaded extension 22 adapted to screw on the threaded nipple 18. If desired, the bladder or the like 2 may be 30 formed with an enlargement 23 adjacent to the back plate 3 so that should the bladder 2 become accidentally deflated, the pad would 35 not wholly collapse and still be, to a certain extent, effective. The appliance is adapted to be worn in the usual manner and may be provided with either one or two pads according to whether it is required for a single 40 or double rupture. The desired pressure in the pads is obtained by screwing the pump 19 on to the threaded nipple 18 and squeezing the spherical portion of the pump in the well known manner, after the member 17 is 45 given a certain rotation to bring the parts into the position indicated in full lines in Figure 5. This rotation of the member 17 will allow the ball 20 to be free between the orifices in the parts 16 and 17 and act as a 50 valve in the well known manner. The air entering the valve 21 in the pump 19 will pass the valve 20 into the bladder or the like 2. When sufficient air is forced into the bladder 2 to obtain the required pressure, the member 17 is screwed up on the member 16 so as to lock the ball 20 in the position shown in dotted lines in Figure 5. The pump 19 can now be unscrewed and removed from the member 17 until again required. 55 Should the pressure of the pad be more than desired, the member 17 can be unscrewed slightly to allow a quantity of air to escape from the bladder 2. The member 17 being again screwed up to prevent leakage. The 60 pressure of air in the bladder 2 will press

the pad outwardly and against the body of the wearer and the back plate 3 will form an effective seating for the pneumatic pressure in the casing 1. The member 17 of the valve connected to the resilient extension 13 70 of the bladder 2 is adapted to be tucked into a suitable pocket 23^a arranged on the body portion of the belt. This pocket 23^a is formed by hemming over a portion of a loop 24 which is adapted to slide on the body 75 belt 7. The sliding loop on the belt may be made of any suitable material such as webbing or velvet.

In a modified construction as shown in Figures 6, 7 and 8, the pad members or the like are constructed entirely of rubber. The portion 25 taking the place of the back plate is of substantially thick rubber or other suitable material such as metal reinforced rubber. To this rubber plate 25 is vulcanized or secured in any other convenient manner a substantially hemispherical thin rubber bag 26 which is adapted to provide a resilient pneumatic pad. This pad is integrally formed with the resilient tubular connection 27 which is fitted with a suitable valve 28 adapted to act in the manner previously described. The back plate 25 is provided with a pair of vertical slots 29 for the reception of the body belt or the like which in this case may be made of rubber or of such material that the truss can be worn during bathing or at night. The back plate 25 is also provided with a horizontal slot 30 for the reception of the hip belt 10. Each pad member 26 is preferably covered with a piece of washleather or other suitable flexible material 31 of substantially hemispherical shape. To the washleather 31 is sewn or otherwise secured four pieces of tape or the like to provide two pairs of securing members 32 and 33. The ends of the oppositely arranged tapes 32 and 33 are provided with co-operating fastening devices 34 such as press-button fasteners so that each pair of members can be detachably connected together. The side tape members 32 are adapted to pass through the vertical slots 29 in the base member 25 and be detachably connected to each other at the rear 100 of the base 25 and the two vertical tapes 33 are adapted to be detachably connected to each other at the rear of the base member 25 in a similar manner. The lower tape is adapted to pass through the horizontal arranged slot 30 in the base member 25. Thus the washleather covering or the like 31 can be readily removed from the pad member 26 when desired. The body belt is adapted to be threaded through the vertical slots 29 as in the previous construction, and this belt may be provided with loops having pockets for the valves 28 as before mentioned. The pressure of the air in the pads is obtained by means of the pump previously described and 115

this pressure may be relieved by unscrewing or partly unscrewing the valves. In use and assuming it is desired to wear, for instance, a waterproof truss and that the pads are 5 arranged on a belt of webbing or like material, the pad members can be readily removed from the belt; the hip straps 10 and the washleather portions 31 of the pads may also readily be removed. The two rubber 10 pad members of, for instance, a double truss can be readily placed on a leather or rubber body belt which may or may not be provided with hip straps. In this instance, the loop members 24 forming the pockets for 15 the valves of the pad members may be constructed of rubber or like waterproof material or they may be omitted. Thus the truss can be readily converted so that it may be worn at any time. It is also unnecessary 20 to alter the pressure of the air in the pads when they are taken off one belt and placed upon another.

In a further modified construction as shown in Figures 9 and 10, the hemispherical pad members 1 are secured around their 25 peripheral edges between plates 3 and 4 of metal preferably aluminum. This back plate 3 is provided at opposite sides with slots 6 of substantially rectangular shape 30 for the reception of the ends of the body belt 7 of any suitable material, such as webbing or elastic material. In this instance, the ends 35 of the belt 17 are hemmed over to provide loops to secure the back plate 3 35 thereto. The hip belt 10 is passed through the horizontal slot 9 and hemmed over as in the previous construction. The back plate 3 is formed with a central aperture 36 of substantially circular shape and this circular 40 shaped aperture 36 is adapted to be closed by the cover plate 37 pivotally mounted at 38 on the said base plate 3. This rotatably mounted cover plate 37 is of substantially circular shape and is adapted to be locked in 45 position on the base plate 3 by a pin 39 on the said base plate 3 engaging in a cam shaped slot or recess 40 formed in the cover plate 37. Within the resilient casing 1 of the pad member which is preferably constructed of washleather or other suitable 50 material is adapted to be placed a bladder or the like 2. This bladder 2 is adapted to be inserted in the casing through the hole 36 provided in the back plate 3. The resilient 55 extension 13 carrying the portions 16 and 17 of the valve member is adapted to project through a suitable slot 41 cut in the hinged cover plate 37 and the valve is adapted to be retained in position against the belt 7 by 60 means of a sliding loop 24 arranged thereon. In this instance, the bladder 2 can be readily removed and replaced by partially rotating the pivoted plate 37 on its pivot to permit of the bladder 2 to be drawn out 65 through the opening in the said plate 3.

It will be understood that any form of valve may be employed for use in connection with the above described pads or bladders, the most convenient form is shown in Figure 5. In the modified construction, shown 70 in Figure 11, the valve comprises a pair of cooperating threaded members, the member 16 being secured to the flexible connection 13 of the bladder 2 as previously described and the other member 17 being formed with 75 a nipple 18 on which is adapted to be screwed any suitable form of pump. The member 17 is formed with an interior tubular extension 42 and is provided with a plurality of air inlet openings 43. Between the extension 42 and the portion 16 is arranged 80 a suitable form of resilient washer 44 which is adapted to prevent the exit of air through an aperture 45 in the member 16 when the said washer 44 is screwed up tightly between 85 the extension 42 and the portion 16. When it is desired to pump air into the bladder 2 the portion 17 is partly unscrewed from the portion 16 connected to the bladder 90 to permit the air to pass through the orifices 43 around the threads of the member 17 past the washer 44 and through the orifices 45 into the bladder. When sufficient air is pumped into the bladder the member 17 is 95 screwed upon the member 16 to secure the washer 44 therebetween and close the orifice 45.

What I claim is:—

1. In a surgical truss or the like, a backing plate formed with belt receiving edge 100 slots, a flexible casing removably secured to said backing plate, an inflatable pad arranged in said casing, and means projecting through said casing and communicating with said inflatable pad to permit the connection of an inflating means thereto for inflating the pad at will.

2. In a surgical truss or the like, a backing plate, an inflatable pad, said backing plate being formed with an opening through which the pad may be bodily inserted, an inflating tube carried by and projecting from the pad, and a cover plate carried by the backing plate to close the opening in the latter, said cover plate being formed with a slot 105 to permit the passage of the inflating tube.

3. In a surgical truss or the like, a backing plate formed with belt receiving edge slots, an inflatable pad removably secured to said backing plate, inflating means carried by and communicating with said pad, and means adapted to be mounted on the belt to receive and support said inflating means.

4. In a surgical truss or the like, a backing plate formed with belt receiving edge slots, an inflatable pad removably secured to said backing plate, a flexible tube carried by and communicating with said pad, a valved nipple projecting from said tube and adapted to receive inflating means, and a 125 130

pocket to receive and support said nipple, said pocket being adapted for connection with the belt.

5. In a surgical truss or the like, a backing plate formed with belt receiving edge slots, a flexible pad cover removably secured to the backing plate, an inflatable pad ar-

ranged within said cover, an inflating tube carried by and communicating with said pad, and means cooperating with the body belt ¹⁰ to receive and support said inflating tube.

In testimony whereof I have hereunto signed my name.

THOMAS BEASLEY.
